UNITED STATES PATENT OFFICE.

SVEN GUSTAF WINGQUIST, OF GOTTERBORG, SWEDEN.

VANE PUMP.

Application filed February 27, 1923. Serial No. 621,578.

To all whom it may concern:

Be it known that I, SVEN GUSTAF WINGQUIST, doctor, a subject of the King of Sweden, residing at Vasagatan 46, Gottenborg, Sweden, have invented certain new and useful Improvements in Vane Pumps, of which the following is a specification.

This invention relates to vane pumps, which comprise a stator and a rotor and 10 working vanes, and has for its object to provide a means whereby the position of the pumping surfaces may be controlled to effect, as desired, either idle running or positive pumping action.

15 According to the invention the extent of the radial movement of the working vanes is regulated by suitable cam surfaces, the position of which with relation to the working vanes may be automatically adjusted by 20 means of one or more centrifugal governor weights acting against a counterbalancing spring or springs.

25 In the accompanying drawing, wherein one embodiment of a vane pump according to this invention is shown; Fig. 1 is an axial section of the vane pump. Fig. 2 is an end view thereof having the side cover removed. Fig. 3 is a cross-section along the line 3—3 viewed from the right in Fig. 1. 30 Figs. 4, 5, and 6 show in enlarged scale various modifications of the cam surfaces 13.

The vane pump shown in the drawing is 35 of the double acting type and comprises in known manner a stator 1, provided with working surfaces 2, 3 and abutments 4, 5. Within such stator is rotatably mounted a rotor 6, provided with radially movable vanes 7, said vanes carrying guide rollers 8, which co-operate with internal cam surface 40 10, provided in the stator cover 9, to positively limit the outward movement of the vanes. The vanes 7 are acted on by springs 11 tending to maintain the rollers 8 in contact with the aforementioned cam surface 10 45 and by this means the vanes at the proper radius to contact with the working surfaces 2 and 3. The vanes 7 are according to the invention each provided near their inner extremities with an integrally formed guide lug 12, co-operating with eccentrically disposed internal cam elements 13, preferably combined in a common cam ring 14 rotatable with relation to the rotor 6, whereby all the vanes will be under common control. The 50 55 cam ring 14 supported by arms 19 extending radially from a central hub portion 20

of special form, the object of which will be presently made clear. Pivotally connected to the rotor 6 are bell cranks 21, one arm 15 of each being formed as a governor weight 60 which is acted upon in the direction of the rotor center by a tension spring 16 fastened to the rotor. The other arm 17 of each bell crank has a tooth-like formation engaging a corresponding depression 18 in the central portion 20 of the rotatable ring 14, so that a movement of said bell crank will cause a corresponding rotation of such ring. If, for example, the arms 15 of the bell cranks be swung outwardly under the action of 70 centrifugal force the ring 14 with its individual vane controlling cam surfaces 13 will be rotated in a clockwise direction, which is obviously the case as shown in Fig. 3. The cam surfaces 13 have such a form as 75 to permit upon a rotation of ring 14, a progressively greater or lesser radial movement of the working vanes 7, depending upon the direction of rotation of the ring. The cam ring in the position illustrated permits the maximum outward movement of the vanes 7 in which position they come in contact with the working surfaces 2, 3, in the stator 1. In Fig. 3, the governor weights 15 are shown as having at a certain speed, 80 through the action of centrifugal force, been moved outwardly against the action of the spring 16, causing arms 17 to rotate the ring 14 carrying internal cam surfaces 13 to the position described in which contact may 85 exist between the working vanes 7 and the working surfaces 2, 3. In this position the pump is functioning with full efficiency. If now we suppose the speed of rotation of the rotor 6 to be decreased, the centrifugal force 90 of the weights 15 will also decrease and said force will, at a certain reduced speed of rotation, be overcome by the tension of the springs 16. The resulting movement of the bell cranks 21, causes the cam ring 14 to 95 be rotated to a position in which the radial movement of the vanes 7, will be limited, so that contact with the working surfaces cannot take place and, consequently, the pump will run idle or at greatly reduced 100 efficiency depending upon the clearance between the vanes and working surfaces. By the described control of the vanes 7 by means of the cam ring 14, the radial movements of the vanes take place smoothly and without 105 any risk of shock against the working surfaces 2, 3.

65 70 75 80 85 90 95 100 105 110

Obviously, the invention is applicable to pumping devices in which it is desired to effect idle running at more than one speed range, with a positive pumping action between such idle running ranges, or devices in which it is desired to effect idle running above a certain speed. In the latter case the cam surfaces 13 should be designed in such manner as to permit, in the position which they occupy up to a certain speed, contact between the working vanes and the working surfaces, but in their position at a higher speed, through their automatic movement, to prevent such contact. In the former case two ranges of idle running, for example, may be provided by designing cam surfaces 13 with two vane lifting humps with a non-lifting dwell between, which portions may be successively brought into action as the cams are caused to move in one direction or the other by a change in the speed of rotation of the pump with the consequent automatic shifting of the governor weights as has been fully explained.

Throughout the foregoing specification, and in the following claims, the terms "rotor" and "stator" are used merely in the relative sense. In the carrying out of the invention it is obviously immaterial as to which of the two co-acting elements, between which the pumping action occurs, is stationary or whether either be absolutely stationary, the only requirement being that as between the two there is a relative motion, or, as has been stated, one with respect to the other is relatively stationary.

It is to be understood that the invention is not limited to the preferred embodiment which is described in the foregoing, but is susceptible of various adaptations and modifications without departing from the spirit of the invention and within the scope of the following claims.

What I claim as new and desire to secure by Letters Patent of the United States of America is:—

1. In a vane pump comprising a stator and a rotor and working vanes movable radially or substantially radially in one of said parts, the other part being provided with one or more working surfaces co-operating with said radially movable vanes, and means comprising springs and one or more movable weights acted on by said springs and by centrifugal force for positively limiting the radial movement of said vanes in the direction towards the said working surfaces.

2. In a vane pump, comprising a stator and a rotor and working vanes movable radially or substantially radially in one of

said parts, the other part being provided with one or more working surfaces co-operating with said radially movable vanes, and means comprising springs, movable weights and cam members adjustably connected to said rotor for positively limiting the radial movement of said vanes in the direction towards the said working surfaces, the position of said cam members with relation to the working vanes being automatically controlled by means of the movable weights acted on by the springs and by centrifugal force.

3. A vane pump comprising a stator, a rotor, and pumping vanes, said vanes performing generally radial movements in the course of the normal pumping cycle, and escape means to permit direct communication between the pressure and suction sides of the pump by preventing fluid tight engagement of the normally coacting working parts of said rotor and stator.

4. A vane pump comprising a stator, a rotor, and pumping vanes, said vanes performing generally radial movements in the course of the normal pumping cycle, and escape means comprising auxiliary vane control means to prevent, at certain speeds, normal operating contact between the vanes and the working surfaces of the pump.

5. A vane pump comprising a stator, a rotor, and pumping vanes, said vanes performing generally radial movements in the course of the normal pumping cycle, and automatic escape means comprising a cam ring, the position of which is controlled by centrifugal force to permit, at certain speeds, direct communication between the pressure and suction sides of the pump by preventing fluid-tight engagement of the normally coacting working parts of said rotor and stator.

6. A vane pump comprising a stator, a rotor, and pumping vanes, said vanes performing generally radial movements in the course of the normal pumping cycle, and automatic escape means comprising a cam ring the position of which is controlled by the spring ballasted centrifugal governor to permit, at certain speeds, direct communication between the pressure and suction sides of the pump by preventing fluid-tight engagement of the normally coacting working parts of said rotor and stator.

In testimony whereof I affix my signature in presence of two witnesses.

SVEN GUSTAF WINGQUIST.

Witnesses:

IHME LOFQUIST,
O. F. LUNDBERG.

Certificate of Correction.

It is hereby certified that in Letters Patent No. 1,538,075, granted May 19, 1925, upon the application of Sven Gustaf Wingquist, of Gottenborg, Sweden, for an improvement in "Vane Pumps," errors appear in the printed specification requiring correction as follows: Page 2, lines 77, 86, 94, and 105, claims 3, 4, 5, and 6, respectively, after the word "cycle" insert the words *independently of the working surfaces co-acting with the vanes*, and line 78, claim 3, strike out the word "escape"; same line and claim, after the word "means" insert the word *adapted*; and that the said Letters Patent should be read with these corrections therein that the same may conform to the record of the case in the Patent Office.

Signed and sealed this 18th day of August, A. D. 1925.

[SEAL.]

KARL FENNING,
Acting Commissioner of Patents.
